ANNULAR CORE HEATER

Fred M. Young, Racine, Wis.

Application January 31, 1938, Serial No. 187,823

3 Claims. (Cl. 257—137)

The present invention relates to suspended type unit heaters having an annular core being positioned horizontally and having a fan so the air is discharged downwardly.

The principal objects of my invention are to provide a simple, easily manufactured, quiet and efficient unit.

A further object of the present invention is to provide a cushion mounted motor and a cushion supporting means for the unit.

To these and other useful ends my invention consists of parts, combinations thereof or their equivalents and mode of operation as hereinafter described and claimed and shown in the accompanying drawings in which:

Fig. 1 is a vertical sectional view of my device taken on line 1—1 of Figure 2.

Fig. 2 is a bottom view of my improved unit.

Fig. 3 is a top view of the complete core.

Fig. 4 is a fractional section taken on line 4—4 of Figure 3.

Fig. 5 is a fractional side view illustrating the header inlet and outlet openings.

Fig. 6 illustrates fractionally a modification.

Fig. 7 is a vertical sectional view of the headers of a modification.

Fig. 8 is a sectional view of one of the headers as shown in Figure 7 taken on line 8—8 of Figure 9.

Fig. 9 is a sectional view of the inlet and outlet header taken on line 9—9 of Figure 7.

Fig. 10 is an enlarged vertical section of the hanger brackets shown in Figure 1.

Fig. 11 illustrates a modification.

As thus illustrated, the motor is designated by reference character A and the fan by reference character B, the core comprises an inlet header 9 and an outlet header 10, each having screw threaded extensions 11 and 12, member 11 generally acting as an inlet and 12 the outlet for the core. The headers are secured together by means of suitable ears and a bolt 13 (see Figure 5), each header is preferably cast integral from suitable material providing header chambers 14—14 (see Figure 4) and outer tube plates 15—15 into which the ends of tubes 16 are suitably secured.

It will be noted that the tubes are arranged in two vertical rows, each row having a multiplicity of closely spaced strip fins 17—17, these fins are similar but a larger number may be placed on the outer row of the tubes for an obvious purpose.

It will be noted by referring to Figure 5 that the fins and headers are of equal width, thus to

provide a suitable surface for contact with annular retainer plates 20 and 21. These plates are made to project slightly past the outer edge of the fins 17 (see Figure 6) providing room for bolts 22 thus the headers and fins may be tightly held between the plates. Plate 20 preferably extends a short distance inwardly past the inner edge of the fins as illustrated in Figure 6 and is curved downward as at 23 thus to cooperate with the fan blades to increase efficiency and avoid air noises.

Plate 21 from its point of contact with the fins is made in the shape of an inverted annular cone as at 24. Transversely in section, member 21 at 24 is formed in a single curve and extends downwardly and inwardly to within a short distance of the motor shaft (see Figure 1). Thus air will be caused to enter the outer edge of the core as indicated by arrows in Figure 1 and caused to move downwardly and inwardly by the vacuum created by the fan and the shape of member 21.

I cushion support the unit preferably by means of two rods 25—25. I provide U shaped brackets 26, which are secured to plate 21, each having an orifice and two composition washers 27—27. An I bolt 28 is provided having washers 29 and nuts 30—30 making up an assembly as clearly indicated in Figure 10 whereby the unit is cushion supported by means of bars 25 which are hooked into members 28, thus to prevent transfer of noisy vibrations and to adequately insulate the unit from its support.

In order to equally distribute the air to the fan blades I provide preferably a curved partition 35 being supported to member 21 by means of spaced brackets 36 which are preferably made from flat metal and placed edgewise to the direction of air flow.

The motor A is cushion supported to member 21 in the following manner: Preferably four depressions 37 are formed in member 21 as clearly illustrated in Figure 1, each having a central orifice and being provided on opposite sides with composition rubber washers 38. The design is very similar to that shown in Figure 10 whereby the motor is cushion held snugly to the support through motor bolts 39. The housing 40 of motor A is provided with projections 41 having flat surfaces which rest on the upper side of the upper composition washers, thus when the bolts are made taut, the motor will be securely held into position whereby there will be no metal contact between the motor and the unit, thus to

prevent any vibrational noises being conducted to plate 21.

Plate 21 terminates a short distance from the motor shaft as at 42 as illustrated in Figure 1, thus there will be passage of a small volume of air over plate 21 to the fan through the opening 42 whereby the motor will be adequately cooled and the temperature above the unit held to about the temperature of the room. As thus designed, member 21 and the fan blades only will be subjected to heated air.

As thus illustrated, it will be noted that the heating or cooling liquid or gas may enter at inlet 11 and pass out of the core at 12. The eight tubes being connected in multiple.

In Figures 7, 8 and 9, I illustrate a modification wherein the inlet and outlet connections are positioned in one header only, this header being designated by reference character 45 having a centrally positioned partition 46, the inlet above this partition being designated by reference numeral 47 and the outlet below the partition is designated by reference numeral 48.

Thus it will be seen that the heating or cooling liquid will be caused to enter the four upper tubes and pass around the circle into header 49 and then pass through this header as indicated by arrow in Figure 7 into the four lower tubes of the core and then pass around the circle in the opposite direction into the header 45 below partition 46 and then be discharged at outlet 48, the length of travel of the heating or cooling medium is double to that shown in the other figures.

I may elect to still increase the length of travel through the core as indicated in Figure 11 by positioning partitions in the headers as indicated, thus as indicated by arrows the entering heating, or cooling medium will first pass from outlet 47 around the circle through two tubes and then return through the next two tubes from whence it will be caused to pass around the third row of tubes in the same direction as in the first row and then again be conducted around the circle to outlet 48 thus the present design may be used for a single multiple connection through the tubes, a multiple series connection, or a series connection.

Clearly the principal objects of the present invention are to provide an annular core and means to efficiently heat the recirculated room air and discharge the air fan like toward the floor of the room, to maintain the room temperature above the unit and to insulate against noise.

One of the advantages of the present invention is that each vertical row of tubes is provided with individual fin strips, thus the fin strips on the outer row of tubes may be spaced the same as the fin strips on the inner row of tubes.

I have illustrated the preferred form of core.

I may however, elect to make use of some other form of core, many of which are known to the art, and while the present invention contemplates discharging the air downward, under some conditions I contemplate reversing the angle of the fan blades so as to discharge the air radially. These and many other modifications may clearly be made without departing from the spirit and scope of my invention as recited in the appended claims.

Having thus shown and described my preferred form of invention I claim:

1. A heat transfer device of the class described, comprising an annular core having means for moving air radially therethrough, said core comprising two or more rows of tubes each row comprising a number of tubes in transverse alignment and each row of tubes having a multiplicity of closely spaced strip fins through which the tubes extend forming independent cores and being positioned one within the other, individual headers to which the adjacent ends of said rows of tubes are operatively connected, said headers at their adjacent sides being in juxtaposition, the adjacent surfaces being at a considerable angle transversely to thereby provide narrow and wide oppositely positioned ends, inlet and outlet openings in the wide ends of each header, projections on adjacent sides of said headers having registering apertures, a bolt in said apertures whereby said headers may be securely bound together.
2. A device as recited in claim 1 including; said headers being substantially the same length as said fins, plates positioned on opposite sides of said cores and headers and having means to firmly bind them therebetween.
3. A heat transfer device of the class described, comprising an annular core having means for moving air radially therethrough, said core comprising two or more rows of tubes each row comprising a number of tubes in transverse alignment and each row of tubes having a multiplicity of closely spaced strip fins through which the tubes extend forming separate cores, the cores being positioned one within the other, individual headers to which the adjacent ends of said rows of tubes are operatively connected, one of said headers having a transverse partition wall separating the tubes of each core in two groups, inlet and outlet connections on opposite sides of said partition whereby the cooling or heating medium will be caused to travel sinuously through said groups of tubes in series, said headers being substantially the same length as said fins, plates positioned on opposite sides of said cores and headers and having means to firmly bind them therebetween.

FRED M. YOUNG.
